UNITED STATES PATENT OFFICE.

ADELBERT L. REYNOLDS, OF NEW YORK, N. Y.

MIXING DEVICE FOR GASEOUS FUEL.

1,281,939.

Specification of Letters Patent. Patented July 3, 1917.

Application filed September 19, 1913. Serial No. 790,598.

To all whom it may concern:

Be it known that I, ADELBERT L. REYNOLDS, a citizen of the United States, residing in the borough of Manhattan, city, 5 county, and State of New York, have invented certain new and useful Improvements in Mixing Devices for Gaseous Fuel, of which the following is a specification.

My invention has reference to improvements in the vaporization of gaseous fuel delivered from a carbureter to the cylinder of an internal combustion engine. Internal combustion engines are notoriously inefficient at low speeds, part of this inefficiency 10 resulting from poor carburetion at reduced speeds. It is the aim of my device to produce a uniformly efficient explosive mixture throughout the practical range of speed of the engine with which it is associated. My 15 device is particularly applicable to automobile or motor-boat engines, which must contend with either a constantly changing speed or load, or both, particularly since it is desirable to control the speed of the motor 20 under these varying conditions by throttling rather than by gear-shifting. Numerous devices have been proposed for supplying an explosive mixture which will enable the engine to be run efficiently at low speed, thus 25 doing away with gear shifting as far as possible, but these devices are all open to the objection that when applied to existing installations they reduce the size of the opening at the entrance to the intake pipe, and, 30 as a consequence, seriously impair the efficiency of the engine at high speed and frequently reduce the full or overload capacity. My invention is directed to the provision of 35 a device which will insure a delivery of the fuel into the engine cylinder in a highly vaporized state at all times, regardless of variations in the speed of the engine, and without any appreciable interference with the flow of the fuel. This I obtain by caus- 40 ing the particles of liquid to impact against one another, as they are passing from the carbureter into the head-end of the cylinder.

The result will be that any large globules of raw fuel will be completely disintegrated 45 and the mixture will enter the cylinder in a finely divided homogeneous mass, thus insuring immediate and complete vaporization. My improved vaporizing device will be found ready of application to any type of 50 engine and carbureter, and because of its extreme simplicity of construction will be

found exceedingly cheap to manufacture, and consequently capable of being placed on the market at a very slight cost.

In the accompanying drawings which 60 form part of this specification, Figure 1 is a side elevation of the mixing device shown as applied to a carbureter at the point where the outlet pipe is connected to the intake pipe of the engine; Fig. 2 is a view in plan; 65 Fig. 3 is an enlarged detail view showing the intake pipe in section.

Similar characters of reference refer to similar parts throughout the several views.

The reference numeral 1 designates a carbureter of the ordinary or Schebler type, having a nozzle 2 in which is located a throttle valve 3, the valve in this instance being of the butterfly type. A pitman 4 connecting with a throttle lever, not shown, 70 serves to open and close the valve. The sides of the nozzle 2 are formed with flanges 5 and 6 which correspond with similar flange members 7 and 8 on the end of the intake pipe of the engine for the reception of the 75 securing bolts 10 and 11, which couple the carbureter and the intake pipe. At the point of connection between the outlet pipe of the carbureter and the intake pipe, I provide a plate 12 secured thereto by means of 80 the bolts 10 and 11. In order to insure a tight joint, I may provide gaskets or washers 13 and 14 located on each side of the plate. As shown, the plate 12 is in the form of a thin sheet of metal having bolt holes 85 15 and 16 and a central orifice 17 corresponding in size with the bore of the intake pipe. Projecting from the plane of the plate and into the intake pipe are a suitable number of homologously disposed 90 blades 18 and 19. The orifice and the blades are formed by cutting a central opening in the plate having the general outline of an ellipse and corresponding in its major axis to the diameter of the orifice, and by cutting 95 slits partially along the circumference of a circle having this diameter. The sectors thus formed are bent along their uncut portions so as to incline at all points toward axial foci above the plane of the plate and 100 spirally curved with respect to the central axis of the orifice, forming curved blade members which depend from the periphery of the orifice and project into the intake pipe. It will be obvious that the blades and 105 the orifice may be formed in one operation by the use of a suitable die. In the present

instance I have shown a pair of blades projecting from opposite points on the wall of the orifice, but I do not desire to limit myself in any way to this construction, as it is obvious that the number of blades may be increased or diminished at will without effecting a change in principle of the operation of my device.

The operation of the device is as follows: 10 The valve 3 having been opened by means of the pitman 4 and throttle lever, the mixture is drawn through the outlet pipe 2 of the carburetor until it strikes the blades 18 and 19, from whence it will be divided into a 15 plurality of streams, owing to the peculiar disposition of the blades with respect to the orifice. The central portion of the current will pass through the opening between the blades without any interference whatsoever; other portions of the current will be deflected toward the wall of the pipe, owing 20 to the inclination of the blades to the axis of the orifice; and to still another portion will be imparted an angular deflection with 25 respect to the said axis, due to the inclination of the blades from the plane of the orifice. The combined effect of all these several currents, having different directions of movement, will be to produce a vortical action 30 in the current which will cause the particles of liquid or otherwise not completely vaporized fuel to impact against each other and thus be disintegrated into exceedingly minute particles. The general effect of the 35 relation of parts is such that the central portion of the ascending gas column traveling through a zone of partially rarefied air will entrain those portions of the mixture current which strike the under-surface of the 40 inclined blades, which, owing to their disposition, form an inwardly converging spiral and impart a like movement to the central portion of the current. A portion of the mixture current tends to ascend un- 45 impeded through the central opening between the blades 18 and 19, but other portions, striking the under surfaces of the blades will be deflected along the resultant of their angles of inclination and the lat- 50 eral helical disposition of their surfaces, throwing the particles in a converging spiral movement toward the core of the fixture current and into the zone of highest speed, thus setting up a vortical action about the 55 central axis of the intake pipe instead of

throwing the particles to the outside periphery of the intake where they are subject to condensation. Those particles of fuel that pass between the blades will be entrained in the air eddies induced by the 60 blades and carried into the rotating movement set up in the mixture column. The effect of the device is thus to increase vaporization, to eliminate masses of liquid fuel and to permit the combustible mixture to be 65 drawn into the engine in a highly homogeneous condition and thoroughly mixed with air. It will be noted that owing to the fact that the blades project from the wall of the orifice in the plate, the bore of the 70 intake pipe is not materially diminished, and consequently the efficiency of the engine, when running at high speed, is not impaired, a disadvantage present in all similar devices of which the inventor has knowl- 75 edge.

Although I have described certain specific embodiments of my invention and a particular application thereof, yet it will be understood that such description is only for the 80 sake of illustration, and that my invention is capable of broad application and wide modification without departing from the spirit and scope thereof.

Having thus described my invention, I 85 claim:

1. A device of the character described comprising a plate having a central orifice and having a pair of opposed symmetrically disposed homologous vanes therein integral 90 with said plate and bent out of the plane thereof, each vane being in the form of a spiral crescent, the lines of whose outer surface lie in the surface of a cone, said surfaces being bounded by curved lines generated by 95 cutting said cone on intersecting spirals.

2. A device of the character described comprising a plate-like body having a circular orifice therethrough, and integral vanes projecting inwardly across said orifice from opposite sides thereof and out of the plane of the plate-like body, the said vanes having the form of a crescent, the upward horn of each crescent being bent spirally.

ADELBERT L. REYNOLDS.
